COMPOSITE INSULATED WHEEL

William R. Smith, Philadelphia, Pa., assignor to
 The A. C. Gilbert Company, New Haven, Conn.,
 a corporation of Maryland

Application November 4, 1944, Serial No. 561,963

11 Claims. (Cl. 105—122)

1

This invention relates to sectional wheels in which a felly or rim section is electrically insulated from a central or hub section of the wheel and particularly concerns sectional wheel structures and methods of manufacturing the same better suited to mass production of small wheels of very simple construction such as the traction or driving wheels of a toy locomotive or some other car in a toy electric train.

In so-called two-rail electrified toy railroads it is necessary for one of the two track rails to serve as a current feeder while the other track rail serves as a return conductor for the current that energizes the driving motor of the toy locomotive. In order to complete a power circuit through the motor from one track rail to the other, certain traction wheels of the toy cars or locomotive may be conductive as usual and serve as a current collector to maintain the locomotive motor in circuit with the track. Wheels on transversely opposite sides of the same toy car however need to be insulative as between the car body and the track rail on which they roll in order to prevent short circuiting the electric motor. As it is undesirable to make the whole of such wheels out of insulating material it becomes necessary to insulate the rim portion of the wheel from the hub of the wheel.

It is one object of the present improvements to provide a sectional wheel in which the hub section is insulated from the rim section so that the latter section which rolls on the rail may, if desired, be made of metal for maximum protection against wear and breakage or becoming out of round.

Another object is to introduce the necessary electrical insulation into the wheel structure apart from any process of molding or metal casting that is employed in production of the wheel sections, thereby to avoid costly complications of molding equipment and to avoid processes which slow down the speed of output in mass production.

A related object is to introduce a preformed insulative body into the wheel structure by mechanical assemblage of such body with separate hub and rim sections of the wheel.

A further object is to employ a method of mechanical assemblage which will hold the wheel sections fixedly and permanently together in a unified structure without requiring any extraneous fastening means and yet will permit ready disassembly of the wheel sections when desired and their replacement by interchangeable parts. This is a valuable feature in mass production of sectional units where it is often desired to stock

2

interchangeable parts of similar or differing characteristics capable of selective assemblage with one another.

Still further objects are in a toy locomotive drive wheel to dispose the insulative body in the wheel structure in a way to prevent electrical contact between the electrically alive rim of the drive wheel and a closely adjacent reciprocative pitman link pivotally connected to the hub section of the wheel and by means of which rotary motion is transmitted to or from the wheel.

Since this involves visibility of the insulative body or ring at the laterally exterior face of the wheel, a "snappy" or smartened appearance can be imparted to otherwise plain toy train wheels by making the insulative body white or of various bright colors such as is possible without the trouble and expense of surface coating processes if the insulative body is made from any of the commonly available molded plastics.

These and other objects of the invention will become clear in greater detail from the following description of a preferred embodiment and possible modifications thereof, in which description reference is had to the accompanying drawings wherein:

Fig. 1 is a broken away isometric view of a toy locomotive wheel considerably enlarged embodying the present improvements and also shows a section of the toy track rail on which it rolls as well as a fragment of a pitman link for transmitting rotary motion to or from the wheel.

Fig. 2 is a lateral outside view of the bare wheel of Fig. 1 shown in a typical actual size.

Fig. 3 is an edge view of the wheel looking from the right at Fig. 2.

Fig. 4 is a view of the inside face of the wheel.

Fig. 5 is an exploded isometric view of three sections of the wheel drawn on a scale intermediate that of Figs. 1 and 2.

Fig. 6 is a fragmentary view drawn on the same scale as Fig. 1 taken in section on a diametral plane passing through the center of the wheel and the center of the pivotal coupling of the connecting rod.

Fig. 7 is a view similar to Fig. 6 showing a modified construction.

Fig. 8 is a view similar to Fig. 6 showing a still further modified construction.

The structure of my improved wheel shown in Figs. 1 to 6 of the drawings is of sectional or composite character made up of three major parts which I shall refer to as the hub section 10, the felly or rim section 11, and a ring-like member 12 of insulative material.

The rim section **11** may consist of metal, die cast or otherwise formed. For use at the perimeter of a chassis wheel for toy locomotives or other toy railway cars, rim section **11** may be equipped with a guard flange **13** at its inner edge adapted to exert lateral thrust against the rail **14** of an electrified toy railway track.

The hub section **10** contains a central axial bore **17** to receive the wheel axle whose other end will carry a wheel somewhat similar to that herein shown except that it need not have the insulative feature with which these improvements are concerned. After the fashion of the traction wheels of full size rolling stock, hub section **10** may be cast to configure its outer face **18** as shown in Figs. 1 and 2. This imparts the appearance of spokes. Outstanding from hub face **18** there is commonly cast a bearing boss **19** containing a threaded hole **24** to accommodate the screw **20** whose crank pin forming shoulder **21** affords free pivotal bearing for one end of a pitman link **22** whose opposite end may connect to associated moving parts of the impelling gear of the toy locomotive such as a piston rod or some other drive wheel on the same locomotive for transmitting motion to or from the insulative wheel herein concerned. **23** denotes a thrust washer reducing any friction of rubbing that might occur between pitman link **22** and the head of screw **20**.

In the present improvements there is interposed between rim section **11** and the hub section **10** the before mentioned ring-like insulative member **12** assembled in a manner that holds these rim and hub sections fast together in electrically insulated relation without resorting to any extraneous fastening means and without bonding any one section or member to any other section or member by means of a molding or casting operation or in any other way that would preclude their being taken apart at will. Permanent and dependable fixity of the assemblage herein proposed is attained purely by mechanical pressure applied in forcing together the three parts shown in Fig. 5. This might be done in a simple arbor press.

It will be observed that ring member **12** has a barrel portion **26** whose wall thickness tapers, whose outer surface **27** is cylindrical and whose inner surface **28** is conical. This ring member also presents a flange-like shoulder **29** projecting radially outward beyond cylindrical surface **27** and in its assembled position flanking the outer side face **15** of the rim section **11**. The thinnest section of the tapering wall of barrel **26** is preferably at or near the flange shoulder **29**.

Since cylindrical surface **27** is perpendicular to the plane of flange **29** while conical surface **28** slants in relation to such plane there will be a tight wedging effect when, after the ring member **12** is sleeved by the closely fitting cylindrical surface **27**, hub section **10** is pressed telescopically into place as shown in Fig. 6. This forcing of the hub section axially into its assembled position will drag axially on the ring member **12** and cause the hub section to rub in sliding contact with the ring member after the axial movement of the latter is arrested by its flange **29**. Thereafter, relative axial movement between hub section **10** and the rim sleeved ring member **12** will tightly wedge the hub section into the ring member in a telescopic manner and in a direction to squeeze and slightly compress the material of the ring member radially between the wheel sections. For this effect the ring is

preferably hard throughout and need be only minutely tensile if at all in Figs. 6 and 7. In these forms of the invention no stretching of the ring will be occasioned if its cylindrical surface is an exact fit for the matching cylindrical surface of the wheel section, while in Fig. 8 where all surfaces are conical, the ring **42** requires no tensile property at all.

The degree of compression of ring member **12** is also preferably minute and may for practical purposes amount to a squeeze of two to four thousandths of an inch whereby permanent concentric fixity of the assemblage is assured while leaving the parts free to be disassembled by reverse axial forced pressure. True concentricity of the rim section in relation to the bore **17** of the hub section **10** results.

Without intent of prescribing any limits as to sizes or relative fits of parts capable of successful assemblage according to the principles of this invention, the following examples of relative dimensions are considered satisfactory in the art of toy train construction. The rim section **10** may have a cylindrical inside diameter of 1.032" as compared with a diameter of 1.030" for the cylindrical surface **27** of the ring member **12**. The hub section **10** may have a conical periphery tapering from .045" diameter to .955" diameter along an axial length of about $\frac{1}{16}$ " as compared with dimensions of conical surface **28** of ring member **12** tapering in about the same axial length from .940" to .950". It will be seen that the tapers of the hub section and of the insulative ring member may be substantially alike producing, when the hub section is forced home, the before mentioned squeeze or compression of say, .0025" in the radial thickness of barrel **26** of ring member **12**. These dimensions will work satisfactorily if the member **12** is independently molded of an ordinary thermoplastic such as cellulose acetate materials now on the market. Well understood properties of such materials are their very slight degree of compressibility. They also are non elastic to any appreciable degree. Used as herein proposed, the consequent rigidity and resistance to distortion of a ring of such material dependably establishes and preserves without outside assistance true concentricity of the rim section **11** relative to the bore **17** of hub section **10**.

In Fig. 7 there is illustrated a reversal of some of the features of ring member **12** in that the barrel **26** tapers in like fashion to barrel **26** but differs in having an inner cylindrical surface **34** while the outer surface **35** is conical. In this case the flange **36** projects radially inward instead of radially outward with respect to barrel **26**. Thus flange **36** overlies face **18** of hub section **10** instead of overlying the face of rim section **11**. In the modified construction of Fig. 7 the perimeter of the hub section **10** will be conical and may conform to the ring member according to relative fits as above explained.

In either of the herein illustrated forms of this improved composite wheel, the pitman link **22** is effectively prevented at all times from making electrical contact with either the rim section **11** or **11'** by the annular continuity of flange **29** or **36** which intervenes and acts as an insulative spacer between the pitman link and the outside face of the wheel.

An appearance of attractively decorative circular banding of the rim of the wheel will result without any separate process of surface color 75 oring if the body of ring member **12** or **12'** is

composed of white or brightly colored plastic material whose natural surface color contrasts strikingly with the relatively dull surface appearance of the side face of one or both of the wheel sections.

In further desirable modifications of the foregoing constructions, which constructions in a broad sense contemplate the telescopic assemblage of any independently preformed conductive and insulative parts, insulative flange 29 or 36, 10 might be disposed to overlie the inside face instead of the outside face of the wheel or might be dispensed with entirely, the ring member then consisting merely of a tapering barrel-like member. Also both the inside and outside surfaces of the tapered barrels of ring member 12 or 12' might be conical instead of one of such surfaces being cylindrical. In this connection attention is called to Fig. 8 wherein the construction is like Fig. 6 except that the outer surface 41 of the barrel portion of ring member 42 is conical in such angular accordance with the inner conical surface 43 that the wall thickness of the barrel portion of ring member 42 is uniform throughout instead of tapering. In this case, rim section 44 has a conical internal surface fitting and conforming as to taper pitch with the external barrel surface 41 of ring member 42. The following are examples of dimensions of parts that have been found to telescope successfully into one another with press fits to form the assemblage shown in Fig. 8 where the material of which ring member 42 is composed is a moldable thermoplastic material preferably of the cellulose acetate groups known commonly by such trade-names as Tenite 1, Lumarith, Nixonite, etc. The conical bore in rim section 44 may taper from 1.032 inside diameter to 1.022 inside diameter in an axial width of .188". The conical barrel of ring member 42 of insulating material may taper along the same axial width from 1.035" outside diameter to 1.025" outside diameter. The conical bore in ring member 42 may taper from .950" diameter to .940" diameter along an axial width of .218". The conical perimeter of hub section 45 may taper from .955" to .945" along the same axial width.

Axially tapering spacer blocks preformed of insulative material and circumferentially spaced may be substituted for the annularly continuous ring member 12 or 12' and correspondingly wedged between the hub and rim sections of the wheel, such blocks having end shoulders abutting the side face of the wheel to serve the purpose of flange 29 or 36. A press fit of the insulative ring member may serve some of the purposes of these improvements if the barrel 26 has no taper at all. These and all other variations of the basic novelty of construction disclosed herein are contemplated and intended to be covered by the various following claims.

I claim:

1. A sectional wheel of small size for toys embodying in rigid combination, a hub section and a metallic rim section, at least one of said sections having a conical surface facing radially toward the other of said sections, together with a minutely tensile minutely compressible ring comprising a hard barrel of electrical insulating material having a hard conical barrel surface conformingly abutting against said section surface, said barrel being wedged compressively between said sections with sufficient tightness to produce unaided and with concentric fixity a rigid assembly of said ring and sections maintained

by the frictional cling therebetween until said barrel is purposely released from its wedged condition.

2. A sectional wheel as defined in claim 1 in which the said ring has a circular flange abutting the side of one of the said wheel sections.

3. A sectional wheel of small size for toys embodying in rigid combination, a hub section having a conical external surface, and an encompassing rim section having a cylindrical internal surface, together with a minutely tensile minutely compressible ring comprising a hard barrel of electrical insulating material having a hard internal conical barrel surface conformingly abutting against said conical external surface of said hub section and having a hard external cylindrical barrel surface conformingly fitting said cylindrical internal surface of said rim section, said barrel being wedged compressively between said sections with sufficient tightness to produce unaided and with concentric fixity a rigid assembly therebetween until said barrel is purposely released from its wedged condition.

4. The method of making a wheel having relatively insulated rim and hub sections, one of which sections has a conical circumferential face, which involves placing in cylindrical engagement with the other of said wheel sections for reinforcement thereby a firm ring-like body of electrically insulative material having a barrel of axially tapering radial thickness terminating in an anchorage flange, thrusting said conical face of said wheel section while in fitting contact with said tapering barrel sufficiently far in an axial direction to bring said anchorage flange into arrested abutment against said other wheel section, and then thrusting said conical face of the wheel section further axially of said ring-like body until the latter is tightly wedged between said wheel sections.

5. The method of making a wheel having relatively insulated rim and hub sections each having a conical circumferential face, which involves placing in conical engagement with one of said wheel sections for reinforcement thereby a firm ring-like body of electrically insulative material having a barrel whose internal and external surfaces are both conical, and then rubbing said conical face of the other of said wheel sections in sliding contact with said barrel in the proper axial direction to wedge said barrel between said wheel sections.

6. A composite traction wheel for toy electric railway rolling stock, comprising three sections adapted to be telescopically thrust together in assembly including a hub section, a traction rim section, and an insulative ring member sleeved between said sections having an annular flange overlying the outer face of at least one of said wheel sections and having an internally tapering barrel portion increasing in thickness of barrel wall as it extends away from said annular flange.

7. A composite traction wheel as defined in claim 6, in which the said annular flange of the said insulative ring member is composed of solid minutely tensile minutely compressible thermoplastic material colored throughout to appear in sharp contrast with the surface of said rim section adjacent said flange thereby to produce said contrast without coating the surface of said ring member.

8. In impelling gear for a toy electric locomotive, the combination of a traction wheel having a radially inner hub section and a radially outer rim section having a side face of electrically con-

ductive material, a pitman link of conductive material, a crank pin carried in a circular orbit by said hub section and pivotally connecting said pitman link to the latter in a manner to swing closely adjacent the side face of said rim section for transmitting motion between said wheel and associated moving parts of the impelling gear, and an annularly continuous spacer of insulative material on said wheel encircling said crank pin orbit and projecting toward said pitman link sufficiently to guard against contact of the latter with said conductive face of the rim section.

9. In impelling gear for a toy locomotive, the combination defined in claim 8 in which the said insulative material of the said annularly continuous spacer extends between and insulates the said wheel sections from each other.

10. A sectional wheel of small size for toys embodying in rigid combination, a hub section having a cylindrical external surface and an encompassing rim section having a conical internal surface, together with a minutely tensile minutely compressible ring comprising a hard barrel of electrical insulating material having a hard internal cylindrical barrel surface conformingly fitting said cylindrical external surface of said hub section and having a hard external conical barrel surface conformingly abutting against said conical internal surface of said rim section, said barrel being wedged compressively between said sections with sufficient tightness to produce unaided and with concentric fixity a rigid assembly of said ring and said sections maintained by the frictional cling therebetween until said barrel is purposely released from its wedged condition.

11. A sectional wheel of small size for toys embodying in rigid combination, a hub section having a conical external surface and an encompassing rim section having a conical internal surface, together with a minutely tensile minutely com-

pressible ring comprising a hard barrel of electrical insulating material having a hard internal conical barrel surface conformingly abutting against said conical external surface of said hub section and having a hard external conical barrel surface conformingly abutting against said conical internal surface of said rim section, said barrel being wedged compressively between said sections with sufficient tightness to produce unaided and with concentric fixity a rigid assembly of said ring and said sections maintained by the frictional cling therebetween until said barrel is purposely released from its wedged condition.

Certificate of Correction

Patent No. 2,507,483

May 9, 1950

WILLIAM R. SMITH

It is hereby certified that errors appear in the printed specification of the above numbered patent requiring correction as follows:

Column 4, line 28, for ".045" diameter" read *.945" diameter*; column 6, line 56, after the word "including" insert a comma; and that the said Letters Patent should be read with these corrections therein that the same may conform to the record of the case in the Patent Office.

Signed and sealed this 5th day of September, A. D. 1950.
